UNITED STATES PATENT OFFICE

HERBERT E. BUPP, OF MANSFIELD, OHIO, ASSIGNOR TO THE OHIO BRASS COMPANY, OF MANSFIELD, OHIO, A CORPORATION OF NEW JERSEY

THERMO-ELECTRO-RESPONSIVE DEVICE

Application filed May 20, 1926. Serial No. 110,411.

My invention relates to a thermostatically controlled mechanism to control the operation of a switch or other mechanism.

I have shown the device as applied to the 5 operation of a rotatable switch, but for the sake of simplicity, I have not shown the switch in detail, as the device can be used to control the operation of a rotary or other type of switch, as for instance, the operation 10 of the rotary switch as shown in co-pending application, Serial No. 102,653, filed April 17, 1926, in the name of Edgar D. Moore, with which I am familiar and which switch would open and close the circuits to and from the 15 device or mechanism, or the armature of the device may itself be used as a switch to open or close a circuit, which in turn controls the operation of other apparatus at a distance from the device.

20 One of the objects of my invention is to provide a mechanism which can be connected to a circuit, and when the current flowing in the circuit suddenly exceeds a predetermined amount the mechanism will operate to open 25 the switch.

Another object of my invention is to provide in the mechanism a thermo-responsive device to control the operation of the mechanism when the current flowing in the circuits 30 exceeds a predetermined amount for a predetermined time.

A further object is to provide a means of protecting an electric translating device from a dangerous rise in temperature.

35 Another object of my invention is to provide means for rendering the thermo-responsive control independent of changes in temperature of the surrounding air.

When my invention is used in connection 40 with a rotary switch, as set forth above, for controlling the circuits leading to electrically operated translating devices such as motors, lights, etc., it provides a means of protecting the translating device from sudden over- 45 loads and also from loads sufficiently high to cause a dangerous heating of the translating device when not sufficiently high to cause the overload to operate. In other words, it will permit the translating device 50 to carry its maximum safe load.

I have shown certain parts of my invention in the attached drawing in schematic form, as the construction is simple and well known to those skilled in the art, and to make the disclosure in other form than shown, it 55 is believed would merely complicate the understanding of the invention.

My invention resides in the new and novel construction, combination and relation of the various parts herein described and shown in 60 the accompanying drawing.

In the drawings:

Fig. 1 is a plan view, partially schematic.

Fig. 2 is an end view of Fig. 1.

Fig. 3 is a right-hand side view of Fig. 1. 65

Fig. 4 is a left-hand view of Fig. 1.

Fig. 5 is a detail of the thermostatic control with a portion broken away.

Fig. 6 is a sectional view on the line 6—6 of Fig. 5 to show an adjustable member on 70 the thermostatic control.

Fig. 7 shows one of the elements of the thermostatic control.

Fig. 8 shows my device as applied to a rotary switch, referred to before, and to a 75 translating device.

In the preferred construction of my relay, I employ a base member 1, preferably of insulating material. Mounted upon the base 1 is a magnet M, which does not differ in 80 principle from other well known magnets, but which comprises a core 2, end members 3 and 4 secured to the core member 2 by means of screws and secured to the base 1 by means of the screws 5. The end members 3 and 4 85 may both be made of iron, but the end member 3 may be made of other material. The armature 6, which is also of iron and movably secured to the end member 3 by means of the spring 7, is attracted by the end member 4. 90 The base 1 has mounted thereon the terminal posts 8, 9, 10 and 11.

The core 2 is provided with a coil 12 having one terminal connected to the post 8 by the conductor 13 which is preferably concealed 95 within the base 1. The other end of the coil 12 is connected to the post 10 by means of the conductor 14, also preferably enclosed within the base. The coil 12, it will be noted, is connected in series in the circuit between the 100

posts 8 and 10, therefore, all current flowing through the circuit connecting the posts 8 and 10 will flow through the coil 12. This coil I prefer to construct of copper and of reasonably low resistance in order to cut down resistance losses, as it forms a part of the main circuit conducting current whenever the device is in use.

The core 2 is provided at each end with insulating discs 15 and surrounding the core is also insulating material to maintain insulation between the coil 12 and the adjacent metal parts. This construction is well known to those skilled in the art.

15 Mounted on the base 1 is a thermostatic responsive device T which comprises an insulating member 16 secured to metallic standards 17 and 17' by means of the screws 18 and 18'. Mounted on the insulating member 16 is a bi-metal thermostatic element 19 composed of two dissimilar metals whose temperature co-efficients are different. This bi-metal element is well known in the trade. The element 19 is secured to the insulating member 16 by means of the screw 20 and at its distant end is a contact element 21 secured thereto which may be of metal, but preferably of carbon.

Also mounted on the insulating member 16, but spaced from the element 19, is a U-shaped bi-metal thermostatic element 22 (see Fig. 7).

This element is provided with contacts 23 and 23', which are mechanically and electrically connected to the standards 17 and 17' respectively, by being interposed between such standards and the insulating member 16 and held in position by the screws 18 and 18'. At the distant end of the element 22 is a contact member 24 adapted to engage with the contact member 21.

The contact 23 of the element 22 is connected to the post 9 by the conductor 25. The contact 23' is connected to the post 11 by means of the conductor 26. From this it will be seen that the U-shaped bi-metal thermostatic element is connected in series with the circuit connecting the posts 9 and 11 and, therefore, the current flowing through the circuit connecting the posts 9 and 11 will flow through the element 22. If now a translating device, such as a motor, is connected to the posts 10 and 11 and the posts 8 and 9 are connected to the source of supply then under normal operating conditions the same current which flows through the coil 12 will also flow through the U-shaped thermostatic element 22.

60 The magnet core 2 is provided with an auxiliary winding 27 which has one terminal connected to the conductor 14 through the conductor 28 and the other terminal being connected to the thermostatic element 19 through the conductor 29 and the screw 20. 65 It will be noted that under normal conditions

with the contacts 21 and 24 separated that no current would flow through the coil 27, but should the contacts 21 and 24 be brought into engagement then the coil 27 will be connected between two main circuits connecting the posts 8-10 and 9-11. It will also be noted that when the contacts 21 and 24 are connected together that the two coils 12 and 27 will be in series and connected across the opposite circuits. In other words, the main circuits will be connected together through the coils 12 and 27 in series. For this reason I prefer to construct the coil 27 of a high resistance material such as iron, German silver, nichrome, etc., thereby introducing sufficient resistance to prevent an unnecessary flow of current between the mains, but still accomplish the purpose of the device.

One of the objects of my invention is to provide a device which is controlled by temperature changes based upon the current flowing through the device and the time that such current flows, therefore, I find it necessary to provide means of preventing the thermostatic elements from contacting under other conditions than those intended, and I find that if only a single thermostatic element is used that this element is affected by changes in the surrounding temperature, or what might be termed the room temperature, such that if the thermostatic element should be set to operate under a given room temperature and a given current after flowing a length of time that this setting would vary should the room temperature vary. For this reason I employ the two thermostatic elements 19 and 21 so related to each other that the space between the contacts 21 and 24 will remain substantially constant regardless of the changes in the room temperature, as this temperature would affect both elements 19 and 20 alike and, therefore, the space between the contacts 21 and 24 would remain constant or practically so. With the construction shown, in which one element 19 is entire and the other element 22 is U-shaped, I find that for all practical purposes such construction maintains the separation of the contacts 21 and 24 practically constant, but if it is desired to secure more accurate conditions then the element 19 may be made U-shaped similar to the element 22.

One function of the thermo-responsive device T is to protect the translating device X from a too great temperature rise, and as the device may be used with different classes of translating devices which will permit of different temperature raises, I provide means of varying the thermo characteristic of the thermo-responsive device, and I do this by mounting upon the thermo element 22 a rider 30 which is movable upon the element 22 and will increase or decrease the length of the element 22 through which the current can traverse thereby increasing or decreasing

the length of the element 22 which is subjected to the heating action of the current. With a given current the movement of the free end of the element 22 will be greater or less, depending upon whether the rider 30 is closer to the free end or to the fixed end of the element 22. Therefore, by means of the rider 30 I am able to adjust the thermo-responsive device so that it will operate when the temperature of the translating device X has reached a predetermined degree or close thereto.

10 The armature 6 can be made to operate under different conditions by varying the size 15 of the spring 7.

In Fig. 8 I have shown a rotary switch S controlled by the operation of the armature 6, and this switch will control the opening and closing of the main line circuit leading to the contacts 8 and 9. In Fig. 8 the switch S is shown in its open position. When my device is combined with a switch S and a translating device X, as for instance, a motor, the coil 12 will be energized with a normal flow 20 of current insufficient to operate the armature 6 and also insufficient to operate the armature 6 under starting conditions, but if while running the load on the motor X should be increased suddenly to an abnormal amount then 25 the energization of the coil 12 would be sufficient to immediately attract the armature 6 and the switch S would be released to open the circuit from the source of supply.

Also, if the translating device X should be 30 operated under a steady overload so as to endanger the same, but such overload is not sufficient to operate the armature 6, then after such overload had continued for a predetermined time, thereby heating the translating device up to a predetermined amount, then under such operation, when the predetermined temperature had been reached upon the motor, the thermo-responsive device would operate to close its circuit thereby 40 connecting the free end of the coil 27 to the circuit 25, and this amounts to throwing the auxiliary coil 27 across the two sides of the circuit from the source of power, and current will flow therethrough, increasing the 45 energization of the core 2, and at the same time the current through the coil 12 will be increased by a like amount which flows through the coil 27 thereby further increasing the energization of the core 2, and which 50 will be sufficient to cause the armature 6 to be attracted thereby releasing the spring held switch S to open the circuits from the source of power.

From this it will be seen that I have a device 55 for protecting the motor against a sudden overload of a predetermined amount, or to protect the motor at a lower overload after such overload has raised the temperature to a predetermined amount.

The switch S may consist of a rotatable in-

sulating disc 40 and which is held under spring tension when in its closed position, as is usual with snap switches. The disc 40 is mounted on the pin 41 as is also a lever of insulating material 42, which is free to rotate relative to the disc 40. The lever 42 is provided with a handle 43 by means of which the lever 42 is operated. The disc is also provided with four reciprocating contact members 44, 44', 45 and 45' connected together by the spring members 46 and 47 which are held to the plate 1 by the screws 48. These reciprocating contacts are adapted to engage with contacts 49-49' and 50-50', which are secured in the base plate 1. The contact 49 is connected to the post 51 by the conductor 52 and the contact 49' is connected to the post 8 by means of the conductor 53, while the contact 50 is connected to the post 54 by the conductor 55 and the contact 50' is connected to the post 9 by means of the conductor 56.

The armature 6 is provided with a catch 57 which engages with the stop 58 when the plate 40 is rotated to its closed position and holds the plate in such position thereby closing the circuits from 49 to 49' and from 50 to 50'.

To close the switch the handle 43 is rotated in a clockwise direction which moves the lever 42 into engagement with the projecting contact 45 thereafter causing a rotation of the member 40, and this rotation is continued until the catch 57 engages with the catch 58.

If it is desired to open the switch by hand the lever 42 is rotated in an anti-clockwise direction through the medium of the handle 43, and the lower end of the lever 43 being beveled will engage with the catch 57 thereby depressing the armature 6 and permitting the disc 40 to rotate to an open position.

As stated at the beginning of this specification, the armature can be employed to act as a switch in itself, if so desired, in order to operate or electrically control distant apparatus, and this can be brought about by securing a contact a' Fig. 1 to the base member of such construction, as is well known to those skilled in the art, and which will engage with the armature 6 if it is desired to operate with a normally closed circuit or employ a contact as shown at a'' if it is desired to operate on an open circuit. In either case, a conductor would be led from the armature 6 and from the contact a or a' to such device as is to be controlled by the mechanism shown in Fig. 1.

It will be noted that when the thermo-responsive element closes that the two coils upon the core 2 will be thrown in series across the two sides of the complete circuit, but by constructing the coil 27 of high resistance material the amount of current flowing under such conditions will be materially reduced thereby preventing a heavy flow of current.

The coil 27 could be made in the form of a resistance separate from the core 2, in which case it would not add to the turns of wire on the core 2, and this construction is perfectly feasible by properly proportioning the resistance of the said coil and the ampere turns of the coil 12 so that sufficient energization of the core 2 will be secured.

If the conductor 28 is connected to the conductor 13 in place of to the conductor 14 then when the thermo-responsive device closes, the current flowing through the coil 27 will not first pass through the coil 12, but by connecting the coil 27 as I have shown it permits a smaller number of turns in the two coils, therefore reducing the size of the device.

There are a number of modifications in my invention which will suggest themselves to those skilled in the art, therefore, I do not wish to be limited other than by my claims.

I claim:

1. An electro responsive device comprising an electro-magnet, an armature to be operated by the electromagnet, a pair of conductors adapted to be connected to a source of power and to a translating device, a main coil interposed in series with one of said conductors on one side of said translating device to energize said magnet and operate said armature when the current in the conductors exceeds a predetermined value, a thermo-responsive device connected in series with the other conductor and on the other side of said translating device, means to maintain the thermal device substantially unaffected by variations in the surrounding atmosphere, an auxiliary coil to energize the electromagnet having one end connected to the main coil and the other end arranged to be connected to the last said conductor by the thermal-responsive device when the current therein is a predetermined amount for a predetermined time and means to vary the thermal characteristic of the thermal device.

2. An article of manufacture comprising an electro-magnet having a main coil and an auxiliary coil, an armature to be operated by the electro-magnet, a pair of conductors connected to a source of power, the main coil being interposed in one of the conductors to effect movement of the armature when the current suddenly exceeds a predetermined amount, means comprising the auxiliary coil and a thermo-responsive device having a self-heating thermal current switch member arranged to connect the main coil to the other conductor path when the current flowing through the circuits for a time has raised the temperature of the thermo-responsive device to a predetermined value but to maintain said connection open for all temperatures below said value.

3. In combination, a circuit comprising a pair of conductors, a translating device con-

nected to said conductors to receive power therefrom, a switch for connecting said conductors to a source of power, said switch being biased to open position, a catch for holding said switch in closed position, an electromagnet for releasing said catch, said electromagnet having a winding in series with one of said conductors and arranged to energize said electromagnet to release said catch when the current in said winding reaches a predetermined value, a shunt circuit having impedance therein, a thermal element in series with one of said conductors arranged to connect said shunt circuit across said conductors in parallel with said translating device when the current in said translating device persists for a predetermined period of time at a predetermined value less than that required to energize said winding for releasing said catch, said shunt circuit being connected to the end of said winding adjacent said translating device so that current passing through said shunt circuit passes also through said winding to supplement the current passing through said translating device in releasing said catch.

4. In combination, a pair of conductors, a translating device connected to said conductors for receiving power therefrom, a switch for connecting said conductors with a source of power, said switch being biased to open position and arranged when open to break the connection of both of said conductors with said source of power, a catch for holding said switch in closed position, an electromagnet for releasing said catch, said electromagnet having a winding in series with one of said conductors and arranged to release said catch when the current in said winding reaches a predetermined value, a supplemental winding for said magnet having one end thereof connected with the end of said first named winding adjacent said translating device, a thermal element in series with the other of said conductors and arranged to connect the other end of said supplemental winding with said last named conductor to bridge said supplemental winding across said conductors in parallel with said translating device, said thermal element being arranged to close said parallel circuit when the current in said translating device persists for a predetermined period of time at a predetermined value less than that required to energize said first named winding sufficiently to release said catch, the combined effect of said electromagnet windings being sufficient when said thermal element is closed to release said catch.

In testimony whereof I affix my signature.

HERBERT E. RUPP.
